UNITED STATES PATENT OFFICE.

ALBERT M. PLUMB, OF PLATTEVILLE, WISCONSIN.

ORE-SEPARATOR.

1,079,362.

Specification of Letters Patent.

Patented Nov. 25, 1913.

Application filed July 17, 1912. Serial No. 709,847.

To all whom it may concern:

Be it known that I, ALBERT M. PLUMB, a citizen of the United States, residing at Platteville, Wisconsin, have invented a certain new and useful Ore-Separator, of which the following is such a full, clear, and exact description as will enable any one skilled in the art to which it appertains to make and use the same, reference being had to the accompanying drawings, forming part of this specification.

My invention relates to apparatus for separating materials of different specific gravities and is particularly applicable to ore concentration.

It is known that when comminuted material is subjected to intermittent impulses of air or like fluid tending to impart an up and down motion to the particles, those particles having the greatest specific gravity will tend to displace the lighter particles, thus effecting a stratification of the material, and attempts have been made to utilize this method of separation in ore concentrating machines. One prominent defect, however, of all machines of this character with which I am acquainted, lies in the fact that they do not effect complete separation of the valuable ore or concentrates from the tailings or gangue, but deliver a product known as "middlings," which usually comprises the heavier particles of the tailings and the lighter ore particles. This fact makes it necessary to treat portions of the material twice or more to secure the desired complete separation.

It is a particular object of my invention to provide a simple, efficient apparatus which will effect the complete separation of all the concentrates from the tailings in one treatment.

Other objects and advantages of my invention will appear from the following description taken in connection with the drawings which illustrate one embodiment thereof.

Figure 1 is a view of the apparatus taken along the line $x-x'$ of Fig. 2, which is a sectional view; Fig. 3 is a perspective view of a portion of the separating or concentrating chamber of the machine. Fig. 4 is a side elevation of the pressure distributing nozzle.

The separating chamber is formed by side and end walls 1, and an ore supporting screen 2, it being understood, of course, that this screen or support may be constructed in

any suitable way, of any desired material for the purpose hereinafter set forth. Beneath this screen is an air chamber 3, and suitably attached to the walls of this chamber, are screen supporting members 4. 5 is a second air chamber or pressure distributing nozzle which is preferably made flat and with tapering side and end walls as illustrated. It communicates with the chamber 3 through the slot 6 which is of uniform width and extends the entire length of said chamber, and, is also in communication with a source of air pressure (not illustrated). The purpose of making the nozzle of the shape shown is to secure an even distribution of the pressure supplied to chamber 3.

The concentrating or separating chamber has an opening 7 for the discharge of concentrates and an opening 8 at a higher level than 7 for the discharge of tailings. The opening 7 is preferably made adjustable, and, in the machine illustrated, a sliding bar is provided for this purpose. The upper edge of this bar is substantially level and the lower or bearing edge is inclined. It will be apparent, therefore, that when the bar is moved in one direction, the upper edge will be raised and when moved in the other direction, it will be lowered. Both discharge openings may, of course, be made adjustable if desired.

Extending across the separating chamber and to a point near the bottom thereof is a baffle or partition 10, and located preferably at right angles to this partition and immediately above the screen are spaced retaining and guide plates 11.

12 is a hopper for the material to be treated and this hopper is provided with a suitable number of discharge openings 13, adjustable by means of gates 14, controlled by suitable means, such as the threaded rods 15 and nuts 16.

The number, shape and arrangement of the discharge openings, baffles and guide plates may, of course, be modified and still preserve the principle of operation of the apparatus, it being understood that I have attempted to illustrate only the arrangement of parts which now appears to be the simplest and most efficient. The guide plates 11 are not essential to the operation of the machine but do serve to facilitate the movement of the ore particles in the desired direction and to keep the screen level.

The operation of the apparatus is as fol-

lows: Material to be separated is fed into the portion of the concentrating chamber between the partition 10 and the discharge opening 8 and intermittent impulses of air are supplied through the air chambers, imparting an up and down or jiggling motion to the particles. As a result of this action, the ore particles, which have a greater specific gravity than the particles of the tailings, will gradually displace the latter particles, forcing them upward with the result that immediately above the screen, a layer of material will be formed consisting only of ore particles or concentrates and at the top of the bed of material a layer will be formed consisting only of tailings. Between these two layers, there will be a mixture consisting of particles of tailings and of ore particles. If now, additional material is supplied to the concentrating chamber, the ore particles in this material will find their way downward with the result that other ore particles will be forced under the partition 10, thus raising the surface of the concentrate column and causing concentrates to be discharged at opening 7. The added tailings will also cause the upper surface of the tailings stratum to rise high enough to overflow at the discharge opening 8.

It will be understood that when the concentrating chamber is empty, material must be supplied to cover the entire screen in order that the air pressure will be evenly distributed, since practically all of the air would otherwise pass through the uncovered portion of the screen and not properly agitate the material. This requirement may be met by either supplying an initial bed of concentrates, or, simply by supplying the material to be separated and returning to the hopper such of the material first discharged at the opening 7 which contains a mixture of the concentrates and tailings.

It will be observed that in my apparatus, I maintain two or more columns of material of unequal height but of substantially the same weight per unit of cross section. These columns being supported on a level screen, the motion of the particles downward, laterally under the partition 10 and upward to the discharge opening 7, is produced by displacement and the change in relative position of the particles in the concentrating chamber is due entirely to this action and not to inclinations of the support. One result of this arrangement is that the "middlings" stratum is always confined between the partition 10 and the walls of the concentrating chamber and has no lateral motion, thus making it impossible for any material of this character to be discharged. Another important advantage lies in the fact that the rate of feed and the rate of discharge are to a great extent dependent on each other. It requires addition of material to the con-

centrating chamber to produce an overflow at the discharge openings and the point of the discharge from the hopper can be so adjusted that the rise of the surface of the tailings stratum above the normal will tend to check the inflow of material. If the supply of material is stopped for any reason, there will be no discharge of either concentrates or tailings even though the jiggling action continues. A still further advantage of having the weight on the supporting screen uniformly distributed is that a uniform distribution of air pressure is thereby brought about and consequently all portions of the material to be separated are subjected to the desired action.

I am aware that many modifications in the shape, form and location of parts, and in the details of structure, may be made without departing from the spirit of my invention and I, therefore, do not desire that its scope be limited except as pointed out in the appended claims.

Having fully described my invention, what I claim and desire to secure by Letters Patent of the United States is:

1. In an ore separating apparatus, a separating chamber having a level, reticulated bottom and provided with means for maintaining separate columns of material communicating only at a point near the bottom of the separating chamber and with a discharge opening for each column, the lowest of said discharge openings being substantially higher than the highest point of communication between the columns and said discharge openings being so positioned that the weight of the columns of material, when each extends to the level of its discharge opening, will be equal per unit of cross sectional area, means for supplying material to be separated to one of said columns, and means for applying intermittent impulses of air to the entire bottom of the separating chamber.

2. An ore separator having a separating chamber provided with means for maintaining separate columns of material and with discharge openings positioned to keep the weight of said columns per unit of cross sectional area substantially equal, means for supplying material to one of said columns, an air chamber beneath said columns, and a tapering nozzle beneath the air chamber and communicating therewith by a narrow slot extending throughout the entire length of said air chamber, and means for supplying intermittent impulses of air to the air chamber.

3. An ore separator comprising a separating chamber, having a substantially level, reticulated bottom and discharge openings at different levels, means for adjusting the height of one discharge opening, a partition extending across the chamber and to a point

5 nearer the bottom thereof than to the level of the lowest discharge opening, guide plates extending across the bottom of the separating chamber and at right angles to the partition, an air chamber communicating with the separating chamber, a tapering nozzle beneath the air chamber and communicating therewith through a narrow slot extending throughout the entire length of said air 10 chamber, and means for supplying intermittent impulses of air to the air chamber.

4. In combination, an oblong separating chamber having a level, reticulated bottom, a partition extending across the central portion of the chamber in the direction of its 15 length and to a point adjacent to the bottom, means for feeding material to the chamber on one side of and at points adjacent to the partition, said chamber being provided

with a discharge opening on each side of the 20 partition, the level of the lowest of said openings being substantially above the lower edge of the partition and the relative height of said openings being so adjusted that the weight of the columns of material on opposite 25 sides of the partition will be substantially equal per unit of cross sectional area, and means for applying intermittent impulses of air to the entire bottom of the separating chamber. 30

In testimony whereof, I, have hereunto set my hand and affixed my seal in the presence of the two subscribing witnesses.
